UNITED STATES PATENT OFFICE.

JOHN WINFIELD GREENE, OF DEER ISLE, MAINE.

CRINGLE.

SPECIFICATION forming part of Letters Patent No. 310,414, dated January 6, 1885.

Application filed May 8, 1884. (No model.)

To all whom it may concern:

Be it known that I, JOHN W. GREENE, a citizen of the United States, and a resident of Deer Isle, in the county of Hancock and State 5 of Maine, have invented certain new and useful Improvements in Cringles; and I do hereby declare that the following is a full, clear, and exact description of the invention, which will enable others skilled in the art to which it 10 appertains to make and use the same, reference being had to the accompanying drawings, which form a part of this specification, and in which—

Figure 1 is a perspective view of my improved cringle and clew, applied to the edge 15 of a sail. Fig. 3 is a cross-section of the same, and Fig. 3 is a perspective view of the two halves of the cringle separated.

Similar letters of reference indicate corresponding parts in all the figures.

My invention has relation to cringles or clews for the attachment or passage of ropes or reefs in the edges of sails; and it consists in the improved construction and combination of 25 parts of a cringle made of malleable metal in two parts, connected to clamp the sail by means of rivets and metallic bushings inserted through perforations in the two parts, as hereinafter more fully described and claimed.

Cringles as now in general use consist of a 30 piece of rope passed around a grommet or thimble bearing with one side against the outer side of the bolt-rope of the sail and through eyelets in the sail, one piece of rope and one grommet being placed above the other; and this manner of forming the cringle has been 35 proven to have many drawbacks, in the shape of the rope in the eyelets tearing the sail, and by all the weight and strain of the cringle bearing outside the edge of the sail and its bolt-rope; and to obviate these drawbacks I construct the cringle as I will now proceed to describe.

In the accompanying drawings, the letter 45 A indicates a portion of the leech of a sail; and B the bolt-rope, which is secured in the usual manner in the edge of the sail.

C-C indicate two pieces of malleable metal having flat meeting surfaces, having a number 50 of rivet-holes, D, near their edges and in their middle, and having longitudinal grooves E in the middle of their meeting surfaces,

which grooves likewise have rivet-holes, which grooves serve to clamp the bolt-rope of the sail, the two halves of the cringle clamping the sail. The portion G within the bolt-rope 55 has a perforation or clew-eye, H, which is provided with a metallic bushing or grommet, I, and the outer portion, J, outside the bolt-rope has two perforations, K, forming the cringle, 60 through which the reef-tackle passes, one above the other, which may be provided with bushings L, which bushings or grommets serve, together with the rivets M, which pass through the rivet-holes in the grooves and 65 near the edges of the portions of the cringle, to secure the two halves of the cringle together, clamping the sail and bolt-rope. In this manner it will be seen that the strain upon the cringle will be divided between the portion 70 of the sail which is clamped by the cringle and the bolt-rope, and that there will not be the strain tending to sever the bolt-rope from the sail as in the first-described old style of cringle, the weight of the portion of the 75 cringle within the bolt-rope balancing the weight of the portion outside the bolt-rope.

Having thus described my invention, I claim and desire to secure by Letters Patent of the United States—

1. A cringle consisting of two halves having 80 corresponding longitudinal grooves upon their meeting sides, having corresponding clew-eyes in their inner portions, having corresponding or registering cringle-eyes in their outer portions, and having rivet-holes, as an article of manufacture.

2. The combination of the sail, the bolt-rope, the cringle-halves having registering grooves for the bolt-rope upon their meeting sides, 85 having registering clew-eyes in their inner portions and registering cringle-eyes in their outer portions, and having registering rivet-holes, the rivets, and the bushings inserted in the eyes, as and for the purpose shown and 90 set forth.

In testimony that I claim the foregoing as my own I have hereunto affixed my signature in presence of two witnesses.

JOHN WINFIELD GREENE.
